JOHN L. BOARDMAN, OF BILLINGS, MONTANA.

DEVICE FOR FEEDING POWDERED FUEL.

1,173,995.

Specification of Letters Patent.

Patented Feb. 29, 1916.

Application filed April 17, 1915. Serial No. 22,087.

To all whom it may concern:

Be it known that I, JOHN L. BOARDMAN, a citizen of the United States, residing at Billings, in the county of Yellowstone and State of Montana, have invented new and useful Improvements in Devices for Feeding Powdered Fuel, of which the following is a specification.

This invention relates to means for utilizing powdered or pulverized fuel for burning under boilers and furnaces, and pertains especially to a device for utilizing coal dust as a fuel on locomotives.

The principle of the invention depends upon the fact that a certain definite and predetermined amount of oxygen is required for the proper combustion of carbonaceous fuels, and where powdered fuel such as coal dust is used, it is highly essential that the right proportions of air and fuel are maintained uniformly and continuously, irrespective of the joltings, drafts, and other conditions incident to locomotive use and travel, which tend to disarrange and disturb such proportions.

In regard to the present invention it may be said generally that the fuel to be used is first powdered or pulverized and dried, and then stored in an inclosed tank or hopper on the tender of the engine, whence it is fed by a conveyer to a centrifugal fan; the fan mixing it with the proper amount of air for its complete combustion and blowing it into the fire box.

The invention resides in the combination and arrangement of the devices by which the idea of the use of this powdered fuel under the conditions of locomotive use, is made commercially available.

The invention consists of the parts and the combination and construction of parts as hereinafter more fully described and claimed, having reference to the accompanying drawings, in which—

Figure 1 is a plan view illustrating the invention. Fig. 2 is a vertical section on line 2—2 of Fig. 1. Fig. 3 is a section through the dust bin and conveyer. Fig. 4 is a vertical section on line 4—4 Fig. 1, showing the arrangement of the fan and turbine.

A is a bin or hopper on the tender having an inclined bottom with a discharge slot 2 through which the powdered dry dust may be fed by gravity upon an inclined conveyer belt 3. This conveyer belt 3 is of any ap-

propriate construction, preferably of flexible material having flexible slats 4 to prevent the material slipping backward as it is carried upward and discharged on top of the housing of the centrifugal fan 5 by which the dust after mixture with the proper quantity of air is blown through the discharge pipe 6 and nozzle 7 into the fire box 8. In order to prevent slippage of the conveyer 3, the latter is provided with endless side chains 10 running over drive sprockets 11 at the head end of the belt, which sprockets are driven by the gear connections 12 from the steam turbine 13; this turbine 13 receiving its steam from the engine boiler.

The depth of the dust on the conveyer is adjusted by means of a block 15 set in front of the opening in the hopper which is rigidly secured at a predetermined height to allow a greater or less thickness of dust to pass on the belt.

16 represent a series of rollers underneath the belt and below the hopper opening 2 and are for the purpose of supporting the belt against the weight of the dust over the opening in the hopper, and for supporting the belt at the proper distance against the block 15 that strikes the measure of the fuel on the belt. These rollers 16 prevent the belt from sagging and becoming too full. The dust that is carried upward by the belt is dumped on to a sloping gable 18 which allows it to fall or slide over the edge of the fan housing and down to the intake openings 19 of the fan, where it is drawn into and mixed with the air in the fan and then blown into the fire box. The casing 20 of the conveyer projects down to the upper edge of the intake openings, and a pair of wings 21 are provided between the fan housing and this projection of the conveyer casing, which serve to guide the dust to the intake openings. Pan 22 is provided at the lower side of the intake in such manner that it will not interfere greatly with the entrance of air into the fan, yet will catch any dust that may pass the intake. The fan is of the centrifugal type, and is designed to give a quantity of air directly proportional with the number of revolutions of the fan. The latter is directly connected to the steam turbine with sufficient space between the fan and turbine to permit room for the conveyer gearing and at the same time not restricting the intake of the fan on that side. The 110

latter is directly connected to the steam turbine with sufficient space between the fan and turbine to permit room for the conveyer gearing and at the same time not restricting the intake of the fan on that side. The 110

turbine is of sufficient size to drive the fan at the maximum number of revolutions per minute required.

5 The discharge tube 6 from the fan to the fire box is flexible and of sufficient size to permit the required quantity of air to be blown through without excessive velocity, and terminates in the flared metal mouth-piece or nozzle 7, which admits the mixture of fuel and air along the front of the fire-box, without materially changing the area at any place so as to make an excessive velocity at entrance into the fire-box.

10 The fire-box may be of the same type and in fact the same fire-box as is used at present, with the usual fire brick arch 24, but the grates must be practically air tight when closed, and be of the design that may be tipped and emptied through any suitable 15 connections 25, by means of a lever, not shown, in the engine cab. The ash pans are also made air tight when closed, and may be opened from the cab by any well known means, not necessary here to be shown. The 20 fire-box and ash pan are so arranged that but one of them need be opened at the same time, thus preventing the escape of the burning fuel and preventing a sudden rush of cold air into the fire-box.

25 30 Among the advantages gained by the use of this device may be mentioned the following: The fine coal which is now an expense to the coal mining operators may be used with the same ratio of efficiency as the best lump coal; all of the fuel value or heat energy is taken out of the coal and passed through the boiler tubes in the form of heat; the temperature of the fire-box is controlled at will, and may be kept constant, thus saving 35 the wear and tear due to sudden rushes of cold air when the fire door is opened; fuel saving does not depend upon the judgment of the fireman, but is done automatically and mechanically.

40 45 The special features of the invention itself are these: First and foremost, it is adapted to locomotive use. The powdered fuel is taken from the level of the floor of the tender or from below this level if required, to the top of the fan. This is a very necessary item on account of the restricted amount of room available both in vertical and horizontal distance. Powdered fuel is conveyed to the top of the fan and distributed 50 55 equally to both intake openings, thereby putting an equal amount of friction on each intake opening of the fan, and insuring an equal amount of mixture of fuel and air. The conveyer belt is positively driven at a uniform rate of speed with respect to the fan, so that there is absolutely assured a maintenance of the proper proportion of fuel and air at all times no matter how rough and variable the working 60 65 conditions are for the locomotive. Further-

more, by direct gearing of the fan and belt driving means to the turbine a constant speed may be maintained further conducing to efficiency.

Having thus described my invention, what I claim and desire to secure by Letters Patent is—

1. A device for feeding powdered fuel consisting in the combination of a bin having a discharge slot in the bottom, a conveyer belt traveling beneath the discharge slot, and forming a closure therefor, a centrifugal fan to which the conveyer delivers the material, means to admit air to opposite sides of the fan, and a burner nozzle for the fan to receive the mixture of air and fuel, said conveyer delivering the material to the top of the fan and discharging it into the intakes on opposite sides of the fan, simultaneously with the air that is drawn into the fan from both sides thereof. 75 80 85

2. A device for feeding powdered fuel consisting of a bin having a sloped bottom with a discharge outlet therein, an inclined conveyer beneath the outlet, a spacing bar 90 in conjunction with the outlet and adapted to regulate the depth of fuel on the conveyer, a centrifugal fan onto the top of which said conveyer is adapted to deliver the material, said fan having opposite side 95 air inlets, and means for directing the material discharged from the conveyer into the inlets in the fan whereby the air and fuel is drawn into the fan from both sides of the latter, and a burner nozzle from the fan to 100 receive the mixture of air and fuel.

3. A device for feeding powdered fuel to a furnace including a fan having a discharge leading to the furnace and having oppositely disposed side inlets, a source of 105 powdered fuel supply, means to convey the fuel to the fan and simultaneously into said opposite side inlets thereof and means whereby to enable air to be drawn in with the fuel from both sides of the fan. 110

4. A device for feeding powdered fuel to a furnace including a fan having a housing the top of which is gabled, said housing having oppositely disposed side inlets, a casing spaced from and inclosing the fan housing and 115 having side air inlets, means to convey the fuel on top of the gabled housing, means to direct the fuel toward the housing inlets, and means to convey the fuel and air to the furnace. 120

5. A device for feeding powdered fuel to a furnace, including a housing the top of which is gabled, said housing having a pair of opposite inlets in its sides, a shaft having a fan thereon which shaft extends centrally through said inlets, a casing extending over the gable and sides of said housing in spaced relation to said gable and housing sides and having side air inlets which latter register with the respective inlets of the 125 130

housing, means to feed fuel in the space between the gable and casing, and wings arranged in the space between the sides of the casing and housing and converging toward the housing inlets.

6. A device for feeding powdered fuel to a furnace including a fan having a housing which latter has a pair of opposite side inlets, a casing having sides spaced from the housing sides and having air inlets in its sides which air inlets register with the fan

inlets, means in the space between the housing and casing sides to direct fuel to each of the fan housing inlets, and means to feed fuel to the fan housing.

In testimony whereof I have hereunto set my hand in the presence of two subscribing witnesses.

JOHN L. BOARDMAN.
